No. 673,190.

Patented Apr. 30, 1901.

W. I. WOLVERTON.

VEHICLE COUPLING.

(Application filed Aug. 16, 1900.)

(No Model.)

UNITED STATES PATENT OFFICE.

WASHINGTON I. WOLVERTON, OF AVERY, OHIO.

VEHICLE-COUPING.

SPECIFICATION forming part of Letters Patent No. 678,190, dated April 30, 1901.

Application filed August 16, 1900. Serial No. 27,089. (No model.)

To all whom it may concern:

Be it known that I, WASHINGTON I. WOLVERTON, a citizen of the United States, residing at Avery, in the county of Erie and State 5 of Ohio, have invented certain new and useful Improvements in Vehicle-Couplings; and I do hereby declare the following to be a full, clear, and exact description of the invention, such as will enable others skilled in the art to 10 to which it appertains to make and use the same.

This invention relates to certain new and useful improvements in couplings for vehicles, and more especially to that class of such devices employed for connecting the double- 15 tree and the tongue of a vehicle.

The present invention has for its objects, among others, to provide an improved coupling for this purpose which shall require but a single bolt for attachment to the doubletree 20 and permitting of the use of the coupling with poles of greater or less bend. By prior constructions trouble has been experienced by reason of the fact that poles are formed with different bends, in which case the hammer- 25 strap was either too long or too short and one hammer-strap could not be made to serve with varying bends of poles. My present construction, however, allows of the employment of the one hammer-strap with varying forms 30 of poles, the arrangement being such that the hammer-strap adjusts itself to various bends without altering its form or finish.

Other objects and advantages of the invention will hereinafter appear, and the novel features thereof will be specifically defined by 35 the appended claims.

The invention is clearly illustrated in the accompanying drawings, which, with the letters of reference marked thereon, form a part 40 of this specification, and in which—

Figure 1 is a perspective view of a portion of a doubletree provided with my improved coupling. Fig. 2 is a vertical section taken longitudinally of the tongue with the coupling applied, the doubletree being also shown in section. Fig. 3 is a perspective detail of the end of the hammer-strap, looking at the under side.

Like letters of reference indicate like parts 50 throughout the several views in which they appear.

Referring now to the details of the drawings

by letter, A designates a doubletree, and B a pole or tongue which it is designed to couple together by my improvement now to be described. 55

C is a hollow tapered post rising from the strap or plate D, which latter is provided at one end with a hole d for the passage of a bolt E, which serves to secure that end of the said 60 strap or plate to the tongue, as seen in Fig. 2. The other end of this plate or strap is provided with an elongated slot or notch e, as seen best in Fig. 1.

F is a sleeve sleeved upon the post C and 65 formed with the two horizontal plates or arms f and f', as seen best in Fig. 2, which embrace the doubletree upon the upper and underside, and a single bolt G serves to secure the doubletree thereto, as will be seen from Fig. 2, 70 75 the bolt being provided with a nut g, as shown. Seated upon the upper end of this sleeve is a washer H, and the hammer-strap has a portion which is designed to come down over this washer and the upper end of the post and sleeve and cover the same and exclude dust and dirt. This is seen best in Fig. 2, in which I is the annular depending flange on the end of the hammer-strap J, the whole being held against separation by the vertical bolt K, 80 which passes down through the cap or flange I and through the post C, also continuing through the pole B, carrying upon its lower end a nut k, as seen in Fig. 2.

The rear end of the hammer-strap is of 85 novel construction. This is best seen in Fig. 3, in which it will be seen that this end of the said hammer-strap terminates in a substantially horizontal portion L, having the inclined side flanges l and the rectangular opening M, 90 while the space beneath the top of this portion L is formed with a shoulder N, so that the under side is upon two different planes.

O is the front end of the iron which extends from the circle on the tongue, (not 95 shown,) and this end is formed with the substantially semicircular recess o. (Seen best in Fig. 1.) In use this end is confined beneath the end of the hammer-strap, as seen in Fig. 2.

In practice the parts are assembled as 100 shown. The end of the strap O is confined beneath the portion L of the hammer-strap and the bolt P placed in position. It will be noticed that this bolt does not pass through either

the hammer-strap or the strap O, the hammer-strap being intended only to hold these parts firmly down to the wood of the tongue or pole and adjust itself upon the same, according to the varying bends of the poles with which the coupling may be employed. For instance, should the pole have considerable bend the hammer-strap would slip forward on the rear end of the top plate and the slot or recess in the end of the same would permit of the bolt passing through it and allow of the necessary movement or adjustment of the parts relatively to each other.

It will thus be seen that I have provided an improved coupling which can be easily applied, readily adjusted, and yet durable and efficient for the purposes for which it is intended.

What is claimed as new is—

1. In a vehicle-coupling, the combination with a tongue and a doubletree, of a plate with a hollow post, a sleeve upon said post having upper and lower horizontal arms to embrace the doubletree, and a hammer-strap having one end attached to the said post and its other end to the tongue, as set forth.

2. The combination with a strap with hollow post rising therefrom, of a sleeve upon the post and provided with upper and lower arms to embrace a doubletree, and a hammer-strap having one end secured to the said post and its other end adjustably connected with a tongue, as set forth.

3. The combination with a plate for attachment to the tongue, and the coupling connection between said plate and the tree, of a hammer-strap, and means for adjustably connecting the strap to the tongue independent of said plate.

4. The combination with the strap and its hollow post, and the sleeve upon the post with doubletree-embracing arms, of the hammer-strap having a portion with opening and a strap with a slot to receive the securing-bolt, as and for the purpose specified.

In testimony whereof I affix my signature in presence of two witnesses.

WASHINGTON I. WOLVERTON.

Witnesses:

HENRY L. SEAMAN,
FRANK C. SMITH.
